UNITED STATES PATENT OFFICE.

CARL I. YOUNG, OF DENVER, COLORADO.

CABINETMAKER'S CLAMP.

Application filed May 17, 1927. Serial No. 191,983.

This invention relates to improvements in clamps of the general class referred to as cabinetmakers' clamps.

Carpenters and cabinetmakers are frequently called upon to do jobs that require the use of clamps and several different kinds of clamps are manufactured and sold for this purpose.

It is the object of this invention to produce a clamp that shall be of simple and substantial construction and which can be quickly applied to and removed from the work.

The above and other objects that may become apparent as the description proceeds are attained by means of a construction and an arrangement of parts that will herein-after be described in detail and reference for this purpose will now be had to the accompanying drawing in which the preferred embodiment of the invention has been illustrated and in which:

Fig. 1 is a plan view of the device;

Fig. 2 is an enlarged longitudinal section taken on line 2—2, Fig. 1;

Fig. 3 is a transverse section taken on line 3—3, Fig. 1;

Fig. 4 is a section taken on line 4—4, Fig. 1;

Fig. 5 is a section taken on line 5—5, Fig. 4;

Fig. 6 is a view showing a slightly modified construction; and

Fig. 7 is a section taken on line 7—7, Fig. 6.

The improved clamp as illustrated on the drawing consists of two levers 8 and 9 which are duplicates but are reversely arranged. These levers have been shown as constructed from wood, but they may be made of iron or steel, if desired. A metal bar 10 is located on each side of the levers and have their ends pivotally connected to the latter by rivets 11. The pivots 11 may be located at any convenient point between the ends of the levers but are preferably nearer to the larger ends 12 than to the smaller ends 13.

A guide block 14 is located between the transverse bars 10 and is secured to the latter by means of rivets 15. This guide block is spaced equidistantly from the pivots 11 and is provided with an opening 16. A nut 17 has pivotally attached to its opposite sides two pairs of links 18 whose other ends are attached to the ends 12 of levers 9 by means of pivots 19. A tubular member 20 has a

portion of its outer surface threaded as indicated by numeral 21 and has threaded engagement with the nut 17, a handwheel 22, or other equivalent means for rotating the tubular member 20 at its outer end. The inner end of member 20 is normally in contact with one side of the guide block 14 and has been shown as provided with a steel ferrule 23 which, however, may be omitted if desired.

Fastened to the ends 13 by means of screws 24 are clamping jaws 25. The ends 13 have a convex inner surface 26 that cooperates with a corresponding concave surface on the jaws (Figs. 1 and 5) so that the jaws may rock to a limited extent and thereby maintain the flat surfaces 27 parallel when spaced apart different distances. The heads of the screws 24 are countersunk in the inner surface of the jaws and the opening through which the screw passes is larger than the screw so as to permit the jaws to rock.

The links 18 are so long that they can not be brought into a straight line but will always be inclined to the same side as shown in Fig. 1. It is obvious that if the tubular member 20 is turned so as to move inwardly and against the guide member 14, that this will produce a force that will move the nut 17 towards the right (Fig. 1) thereby straightening the toggle and moving the clamping jaws together. If an object, like that shown by dot and dash lines in Fig. 1, and indicated by numeral 28 is placed between the jaws, the latter will be forced against it by the action of the toggle when moved by the operation of member 20.

The interior of tubular member 20 is provided with a threaded section 29 (Fig. 2) with which the threads 30 on rod 31 cooperates. The outer end of rod 31 is provided with a crank 32 which has a handle 33. The inner end of rod 31 is provided with a head 34 that is swivelled thereon. When the rod 31 is rotated, it will move axially either towards or away from the jaws 25, depending on the direction of rotation.

Let us now assume that the job involves the problem of securing member 35 to member 28 by glue. Member 28 is first of all clamped between jaws 25 by rotating tubular member 20 so as to straighten the toggle, part 35 is then put into position and rod 31 rotated so as to engage member 35 and force it against part 28. It will be observed that this clamping device comprises

a pair of spaced jaws and means for moving them towards and away from each other so as to clamp and release an object and an independent clamping member movable in a direction at right angles to the movement of the jaws.

In Figs. 6 and 7 I have illustrated a slightly modified form of construction in which the jaws 25 have been replaced by jaws 36 which are shaped somewhat as shown in Fig. 6. These jaws instead of being secured to the levers 8 and 9 by means of screws are each held in place by two round plates 36, each of which is identical with the others and are provided with diametrically located openings for the reception of the pivot pins 38. When the clamp is applied to any article for the purpose of securing the clamp to it, the jaws 36 are so arranged that the pins 38 which pass through the jaws are to be inside of the corresponding pins in ends 13. When rod 31 is operated so as to produce a force tending to move the clamped member outwardly there is a tendency to move jaws 36 to the dot and dash position shown in Fig. 6. Any movement outwardly of jaws 36 produces a toggle effect that increases the clamping force.

Attention is called to the fact that rod 31 is threadedly engaged with the tubular member 20 and that it has no connection with member 14 which merely serves as a guide for rod 31 and as an abutment for rod 20. As a result of this construction the force exerted by rod 31 is added to the force exerted by the tubular member 20 for the purpose of straightening the toggle. If rod 31 had a threaded connection with block 14 instead of with the tubular member, the force exerted by it would not have any effect upon the clamping action of the toggles.

From the above it will be apparent that I have produced a clamping device which can be quickly secured to an article and which is also provided with a clamping

member that moves in a direction at right angles to the other clamping members.

Having described my invention what I claim as new is:

1. A device of the class described comprising, in combination, a pair of spaced levers, a connecting device pivotally connected with the levers intermediate their ends; a clamping jaw secured to one end of each of said levers by means of two links each of which has one end pivoted to the lever and the other end pivoted to the jaw, a toggle mechanism connecting the other ends of said levers, means for changing the angularity of said toggle, said last named means comprising a tubular screw having a threaded connection with the toggle device and having one end in engagement with the connecting device, a clamping member comprising a rod passing through the tubular screw, said rod having a threaded connection with the interior of the tubular screw and means for rotating said rod.

2. A clamp of the class specified comprising, in combination, a pair of spaced levers lying in the same plane, a connecting device pivotally connected with each of said levers at a point intermediate its ends, a clamping jaw movably connected to the adjacent end of each lever by means of two links each of which has one end pivoted to the lever and the other end pivoted to the jaw, a toggle mechanism pivotally connected to the other ends of said levers, said toggle mechanism comprising a nut and two pair of toggle links, a hollow tubular member threadedly connected with said nut, means connected to the outer end of said tubular member for rotating the same, the wall of the opening in the threaded member having a threaded section, a rod extending through the tubular member and threadedly connected therewith and means for rotating the rod.

In testimony whereof I affix my signature.

CARL I. YOUNG.
